ATTORNEY

UNITED STATES PATENT OFFICE.

FERNAND BISSON, OF PARIS, FRANCE.

AUTOMATIC LIGHTER.

Application filed February 8, 1922. Serial No. 534,990.

To all whom it may concern:

Be it known that I, FERNAND BISSON, citizen of the Republic of France, and resident of Paris, France (post-office address 5 58 Rue Amelot), have invented a new and useful Automatic Lighter, which improvements are fully set forth in the following specification.

The object of my invention is to provide 10 a gasoline automatic lighter characterized by the fact that ignition of the wick is effected consequent upon a mere pull exerted on a device with which it is connected and which carries the rubbing surface.

15 A lighter embodying my invention is illustrated, as an example, by the appended drawings, wherein:

Figure 1 is an elevation of my lighter.

Figure 2 is a side view of the same.

20 Figure 3 is a sectional view thereof, partly in elevation:

Figure 4 is a cross section of Figure 3.

Figure 5 is an elevation showing the wick-carrier tank.

25 Figure 6 is a side view of Figure 5.

Figures 7, 8, and 9 relate to a modification.

Referring to Figure 3, it will be apparent that the apparatus comprises a box 1 made of metal or other material and suitably 30 shaped, having at its upper part a notch 2 and an opening 3, the use of which will be hereinafter explained.

Said box 1 is divided into two compartments by a partition 4 secured by any suitable means. In the right-hand compartment 35 is disposed, against partition 4, a strip or bar 5 of pyrophoric material, for instance, ferrocerium, suitably shaped, on which a coil or other spring 6 presses vertically in order to keep the end 7 thereof applied 40 against the edge of the box opposite opening 3.

On the other hand a double blade spring 9 acting on a suitable part 10 which covers 45 it, forces the said bar 5 against partition 4.

In the left-hand compartment, is inserted 50 a gasoline tank 11, suitably shaped and provided with an opening 12 which registers with notch 2 of the box, and is filled with oakum 13 or any other suitable material.

The lower end or edge of this compartment is cut out, whereby the tank can be readily inserted or withdrawn by sliding it in or out.

55 A thin covering plate keeps all parts in position within box 1.

This box, so made up, is fitted into a correspondingly shaped sheath 14, which is provided at its top, above openings 12 and 3, with a suitably shaped opening having 60 protecting guide flanges 16 and at its bottom with a suitable guide in which a closing plate 17 engages.

The wick is carried by a device independent from the one just described, said 65 independent device furthermore carrying the rubbing member proper.

This device is constituted by a suitably shaped head or button 18 which fits between flanges 16. Said button carries a small rod 70 19, with a spur 20, on which rod is secured by a bayonet slot or other means a small tube 22 containing an asbestos or other wick.

Opposite this tube is secured a steel rod 24, carrying adjacent its end one or several 75 claws or hooks 25, which constitute the rubbing or friction member or members. In this rod 24 is made a rectangular slot 26 in which slides a finger 27 designed, due to its shape and size, to prevent wear on the 80 pyrophoric bar 5 as will be hereinafter explained.

Friction rod 24 is inserted through opening 3 into the right-hand compartment, between bar 5 and cover part 10. So positioned, finger 27 is brought to the end of slot 26 remote from hook 25 by its frictional engagement with cover 10 during its passage into the box.

Rod 24 is so shaped that when the finger 90 27 is in the above indicated position, the hook 25 does not rub against the bar 5—any useless wear being so avoided.

Tube 22 is forced down through opening 12 into tank 11, where its wick 23 becomes soaked with gasoline.

When the wick-carrying device is being withdrawn by a pull on button 18, finger 27 is brought back into contact with hook 25 and, since the thickness of the said finger 100 is less than the thickness of the hook, the latter must be in contact with the pyrophoric bar until the time when, reaching opening 3, a spark will occur which will ignite the wick in tube 22, the latter being at 105 this moment also out of the gasoline tank.

It should be noted that (and this is a characteristic feature of my invention) with the aforescribed arrangement the button carries the friction device and the wick, 110 which are independent from one another, so that the pyrophoric material never is in con-

tact with gasoline, which would disintegrate it, a drawback found with automatic lighters hitherto marketed.

Of course, the present description of my 5 lighter is given merely by way of example, and I reserve the right to modify constructional details or arrangements without getting beyond the scope of my invention.

Figures 7, 8 and 9 relate to a modification, 10 wherewith and wherein the wick, instead of being set in a wick carrier tube 22, is directly positioned at 41 in gasoline-soaked cotton-wool 13 and projects from the upper part of the tank through a suitable neck 15 42 between flanges 16.

As with the first described device, button 18 is housed between flanges 16. The shape of said button 18 is always the same, but in order to allow it to protect the wick 41 20 protruding from neck 42, I have provided in it an upwardly and inwardly extending recess 46 of suitable size and shape.

Another characteristic of this constructional modification consists of the fact that 25 in order to simplify manufacturing, I have suppressed on ignition rod 24 the small finger intended as hereinbefore explained, to avoid unnecessary wearing of the ferrocium stone.

It will be obvious that I do reserve the 30 right to mount if I so chose the said finger either on the device shown by Figures 7, 8 and 9, or on the device shown by Figures from 1 to 6.

Having now particularly described and ascertained the nature of my said invention and the manner in which the same is to be performed, what I claim is,

1. In a lighter, the combination of a 40 case having an open end; a pyrophoric body within the case immediately adjacent said end; a rod insertible and withdrawable bodily into and from said case through said end and provided with abrading means for contact 45 with the pyrophoric body to produce sparks during the withdrawal of the rod; a wick adapted to be ignited by such sparks; and means other than the abrading means for preventing contact between said abrading 50 means and pyrophoric body during the insertion of the rod.

2. In a lighter, the combination of a case having an open end; a pyrophoric body within the case immediately adjacent said 55 end; a rod insertible and withdrawable bodily into and from said case through said end and provided with an abrading member for contact with the pyrophoric body to produce sparks; a wick adapted to be ignited by such sparks; and means carried 60 by said rod but separate from the abrading member itself for preventing such contact during the insertion of the rod but permitting it during withdrawal thereof.

3. In a lighter, the combination of a case

having an open end; a pyrophoric body within the case immediately adjacent said end; a rod insertible and withdrawable bodily into and from said case through said end and provided with an abrading member 70 for contact with the pyrophoric body to produce sparks; a wick adapted to be ignited by such sparks; and a movable element for preventing such contact during the insertion of the rod but permitting it during withdrawal thereof. 75

4. In a lighter, the combination of a case having an open end; a pyrophoric body within the case immediately adjacent said end; a rod insertible and withdrawable 80 bodily into and from said case through said end and provided with an abrading member for contact with the pyrophoric body to produce sparks; a wick adapted to be ignited by such sparks; and an element 85 carried by said rod and movable relatively thereto for preventing such contact during the insertion of the rod but permitting it during withdrawal thereof.

5. In a lighter, the combination of a case 90 having an open end; a pyrophoric body within the case immediately adjacent said end; a rod insertible and withdrawable bodily into and from said case through 95 said end and provided with a longitudinal slot and with an abrading member located below the same for contact with the pyrophoric body to produce sparks; a wick adapted to be ignited by such sparks; and a controlling member movable in said slot 100 to prevent such contact during the insertion of the rod, but permitting it during the withdrawal thereof.

6. In a lighter, the combination of a case 105 having an open end; a longitudinal partition within the case dividing the interior thereof into two compartments, one of which provides a tank for an inflammable liquid; a pyrophoric body disposed in the other compartment and terminating immediately 110 adjacent the open case end; an operating button or head; a wick tube carried thereby and adapted to be inserted into and withdrawn from said tank; a wick in said tube to be saturated by the liquid; and a rod also 115 carried by said button and insertible and withdrawable bodily into and from said other compartment through said open end and having an abrading member for contact with the pyrophoric body during the 120 withdrawal of the rod to produce sparks and thereby ignite the wick.

7. In a lighter, the combination of a case 125 having an open end; a longitudinal partition within the case dividing the interior thereof into two compartments, one of which provides a tank for an inflammable liquid; a pyrophoric body disposed in the other compartment and terminating immediately 130 adjacent the open case end; an operating

button or head; a depending member on the under face thereof; a wick tube removably attached to said depending member at its upper end and provided at its lower end with a projecting wick, said tube adapted to be inserted into and withdrawn from said tank; and a rod also secured to said button and insertible and withdrawable bodily into and from said other compartment through said open end and having an abrading member for contact with the pyrophoric body during the withdrawal of the rod to produce sparks and thereby ignite the wick.

In testimony whereof I have signed this specification in the presence of a witness.

FERNAND BISSON.
